Primary Examiner—A. Hugo Word*Assistant Examiner*—I. Simmons*Attorney, Agent, or Firm*—Susan A. Capello[57] **CLAIM**

The ornamental design for a microbial monitoring module, as shown and described.

DESCRIPTION

FIG. 1 is a top and front perspective view of the microbial monitoring module;

FIG. 2 is a top plan view thereof;

FIG. 3 is a front elevational view thereof;

FIG. 4 is a side elevational view thereof;

FIG. 5 is a back elevational view thereof;

FIG. 6 is a bottom plan view thereof; and,

FIG. 7 is a top and front perspective view of the unassembled microbial monitoring module.
